UNITED STATES PATENT OFFICE.

ELIZABETH T. HINCKS, OF CAMBRIDGE, MASSACHUSETTS.

DESIGN FOR A MITTEN.

50,445.

Specification for Design.

Patented Mar. 13, 1917.

Application filed December 13, 1916. Serial No. 136,803. Term of patent 7 years.

To all whom it may concern:

Be it known that I, ELIZABETH T. HINCKS, a citizen of the United States, residing at Cambridge, in the county of Middlesex and State of Massachusetts, have invented a new, original, and ornamental Design for a Mitten, of which the following is a specification, reference being had to the accompanying drawing, forming part thereof.

The figure is a perspective view of a mitten, showing my new design.

I claim:—

The ornamental design for a mitten, as shown.

ELIZABETH T. HINCKS.

Witnesses:

EDWARD Y. HINCKS,
MARY E. FOOTE.
